UNITED STATES PATENT OFFICE

152,259

DESIGN FOR A BRIDGE CRANE

Folke Malcolm Gustafson and John McLeod Little, Toledo, Ohio, assignors to Manning, Maxwell & Moore, Inc., Muskegon, Mich., a corporation of New Jersey

Application November 29, 1946, Serial No. 135,158

Term of patent 14 years

(Cl. D41—1)

To all whom it may concern:

Be it known that we, Folke Malcolm Gustafson and John McLeod Little, citizens of the United States, residing at Toledo, in the county of Lucas and State of Ohio, have invented a new, original, and ornamental Design for a Bridge Crane, of which the following is a specification, reference being had to the accompanying drawing, forming a part thereof.

Figs. 1 and 2 are perspective views of a crane embodying our design and showing respectively opposite sides of the crane.

Fig. 3 is an end view looking from the right in Fig. 1.

The dominant features of the design reside in the portions shown in full lines in the drawing.

We claim:

The ornamental design for a bridge crane, substantially as shown and described.

FOLKE MALCOLM GUSTAFSON.
JOHN MCLEOD LITTLE.
